(57) **CLAIM**

The ornamental design for a wall storage shelf, as shown and described.

DESCRIPTION

FIG. 1 is a perspective view of a wall storage shelf showing my new design.

FIG. 2 is another perspective view of a wall storage shelf.

FIG. 3 is a front view of a wall storage shelf.

FIG. 4 is a rear view of a wall storage shelf.

FIG. 5 is a left side view of a wall storage shelf.

FIG. 6 is a right side view of a wall storage shelf.

FIG. 7 is a top view of a wall storage shelf; and,

FIG. 8 is a bottom view of a wall storage shelf.

The broken lines illustrate portions of the wall storage shelf that form no part of the claimed design.
